UNITED STATES PATENT OFFICE

GEORGE W. HARWARD, OF ELDON, IOWA

LOCKING MECHANISM FOR REVERSE GEARS OF LOCOMOTIVES

Application filed July 3, 1928. Serial No. 290,164.

This invention relates to a locking mechanism for the reverse gear of a locomotive, and it is an object of the invention to provide a mechanism of this kind which effectively locks such mechanism in position and which operates substantially in an automatic manner.

It is also an object of the invention to provide a device of this kind which operates to hold the valve gear in a firm and steady position so that there will be no waste of power due to unsteady movement of the valve gear.

The invention consists in the details of construction and in the combination and arrangement of the several parts of my improved locking mechanism for the reverse gear of a locomotive whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein: —

Figure 1 is a view in elevation and of a diagrammatic character illustrating a locking mechanism constructed in accordance with an embodiment of my invention;

Figure 2 is an enlarged fragmentary view partly in section and partly in elevation illustrating the valve as comprised in my improved mechanism and a portion of the operating means therefor;

Figure 3 is a view similar to Figure 2 showing the valve member in a second position;

Figure 4 is an enlarged fragmentary view partly in section and partly in elevation illustrating in detail the means as herein embodied for directly operating the locking block.

As disclosed in the accompanying drawings, 1 denotes a reverse rod comprised in the conventional type of gear reversing mechanisms for locomotives, and 2 denotes the releasing reverse lever operated in a well known manner by the reversing gear through the medium of the link or bar 3. The lever 2 may

be pivotally mounted at 2' to any desired portion of the locomotive. Supported in any desired manner by the locomotive above the reverse rod 1 is a cylinder C. The cylinder is supported by a bracket 4 which provides a guide for the locking block 5. The lower or working face of this block 5 is provided with the teeth 6 adapted to interlock with the toothed rack 7 carried by the rod 1. This block 5 is secured to and movable with a rod 8 which extends upwardly within the cylinder C through the lower end thereof and carried by the upper or inserted end of the rod 8 is a piston P which is snugly engaged within the cylinder C for rectilinear movement therein. This piston P is constantly urged upwardly within the cylinder C through the instrumentality of a coil spring 9 encircling the rod 8 between the piston P and the lower head of the cylinder C.

When the piston P is moved upwardly under the action of the spring 9, the locking block 5 is moved upwardly a distance to free the teeth 6 thereof from the rack 7 and at which time the reversing gear proper is in release. Rotatably positioned within the cab of a locomotive, or otherwise as may be desired, is a vertically disposed elongated valve cylinder V from which leads an air line 10 discharging within the cylinder C above the piston P. Also leading from the cylinder V at a point in relatively close proximity to the pipe line 10 is a pipe line 11 in communication with a suitable source of air under pressure. At a point spaced longitudinally of the cylinder C and in close proximity to the line 11 is an exhaust port or line 12.

Working within the cylinder V is an elongated valve member M, the major portion of which snugly fitting within the cylinder V with an intermediate portion 14 materially reduced in diameter, said reduced portion being of a length when the valve member M is moved upwardly to permit the pressure within the cylinder C above the piston P to exhaust out through the lines 10 and 12 and when moved in the opposite direction to close the exhaust through the line 12 and to open the line 11 to permit requisite air pressure to be delivered within the cylinder

C to force the piston P downwardly to bring the locking block 5 into desired engagement with the rod 1, or more particularly the rack 7 carried thereby.

5 The upper end of the valve member M is provided with an upstanding stem 15, the outer end portion of which being disposed at all times beyond the upper end of the cylinder V, and said upper and extended end 10 portion of the stem 15 is provided with an arcuate cross member or head 16, the outbow of which being upwardly disposed. In contact with the cross head or member 16 is a reversely curved arcuate cross member 17 carried by the lower end portions of the arms 18. The upper end portions of the arms 18, or those portions of said arms remote from the cross member or head 17, overlie the lower 15 end portion of the lever 2 and said arms 18 have sliding movement in a direction lengthwise of the lever 2. To permit such sliding movement, each of the arms 18 is provided with a longitudinally disposed slot 19 through which are directed the headed members 20 engaged with the adjacent portion 20 of the lever 2. Operatively engaged with the central portion of the head or member 17 is a rod 21 also operatively engaged with the swinging latch 22 carried by the upper end or handle portion of the lever 2.

The heads or members 16 and 17 have rolling contact one with respect to the other and are maintained in such contact by an expandable member 23, preferably a coil spring, interposed between the lower or inserted end portion of the valve member M and a plate 24 arranged within the cylinder V closely adjacent to its lower or closed end 25. This plate 24 is associated with a headed member or shank 26 threaded through the lower or closed end 25 of the cylinder V and provides means whereby upon proper manipulation of the member or shank 26 the tension of the member or spring 23 may be regulated as required. The reverse lever 2 is pivotally secured to a pivot or pintle 2' which is outstanding from a support 27 carried by the cab or housing on the locomotive.

With the valve member M in a position as 50 illustrated in Figure 2 air under pressure is free to pass into the cylinder C above the piston P and maintain the block 5 in locking engagement with the rod 1 whereby the rod 1 is held rigid in any position it may be placed by 55 the reversing gear and, as is believed to be clearly apparent to those skilled in the art to which the present invention appertains, such locking of the rod 1 will hold the valve yoke in a rigid position, thus doing away with that 60 creepy and vibrating movement which is so detrimental to its tractive effort and which has a tendency to cause doubling of hills in many instances. It also obviates the tendency of the valve creeping back and forth 65 during travel of the high speed locomotive

as a result of vibration, pulling valves, etc.

When desired to release the rod 1 so that proper manipulation of the lever 2 will operate the reversing gear, the engineman imposes pull upon the latch 22 resulting in the 70 elevation of the member or head 17 with a resultant upward movement of the valve member M under the influence of the expandable member or spring 23. This upward movement of the member M is of an extent to 75 permit the lower portion of the valve member to close the flow from the pipe line 11 through the cylinder C and opens the exhaust line 12 whereupon the air pressure within the cylinder C above the piston P and in the line 10 will readily exhaust, thus permitting the member or spring 9 to force the piston P within the cylinder C a distance sufficient to disengage the block 5 from the rack 7 carried by the rod 1.

85 From the foregoing description it is thought to be obvious that a locking mechanism for the reverse gear of a locomotive constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

90 I claim:—

The combination with the rod and operating lever comprised in a reverse gear mechanism, of a slidable valve, an intake pipe, an exhaust pipe, a discharge pipe, and locking means connected to said discharge pipe, said valve comprising an elongated cylinder having an intake port, an exhaust port and a discharge port, a pair of spaced pistons in said cylinder, said pistons being arranged for movement within the cylinder to automatically close the exhaust port when the pistons are urged downwardly and to automatically open the exhaust port and close the intake 105 port when the pistons are urged upwardly, a stem secured to one of said pistons, an arcuate head disposed across the outer end of said stem, a complementary arcuate member slidably mounted on said operating lever, and adjustable spring engaging means in said cylinder, said engaging means being adapted to urge the cylinders upwardly to maintain slid- 110 able contact between the arcuate members.

115 In testimony whereof I hereunto affix my 120 signature.

GEORGE W. HARWARD.
